WASHING MACHINE

Osmund Holm-Hansen, Stratford, Conn., assignor to General Electric Company, a corporation of New York

Application March 28, 1936, Serial No. 71,422

5 Claims. (Cl. 259—101)

The present invention relates to domestic washing machines of the type in which washing is effected by the oscillatory movement of an agitator mounted within the tub.

5 In machines of this type a considerable amount of noise has been produced by the mechanism for producing the oscillating movement of the agitator.

The object of my invention is to provide an improved construction and arrangement in washing machines of this type which will result in quieter operation, and for a consideration of what I believe to be novel and my invention attention is directed to the following description and the 15 claims appended thereto.

In the accompanying drawings, Fig. 1 is a sectional elevation of a washing machine embodying my invention; Fig. 2 is a fragmentary elevation in section along the lines 2—2 of Fig. 20 3; Fig. 3 is a top plan view in section along lines 3—3 of Fig. 2; Fig. 4 is a perspective view of the guide for guiding the reciprocating movement of the rack; and Figs. 5 and 6 are sectional views of a modification of the sealing means between 25 the bottom of the tub and the post through which the shaft for driving the agitator extends.

Referring to the drawings, the tub 1 is provided with a bead 2 which rests on the upper edge of a cylindrical skirt 3 which serves as a 30 support for the tub. The arrangement for securing the tub to the skirt comprises a clamping band 5 which engages the bead 2 on the tub and a bead 4 on the skirt and thereby wedges the tub tightly against the upper edge of the 35 skirt. The upper edge of the skirt may have a plurality of spaced slots so that the clamping band will clamp the skirt tightly against the tub. The lower end of the skirt is provided with suitable supporting casters 6. A tubular post 7 40 extends through a central opening in the bottom of the tub upwardly to a point above the normal water level at the top. A vertical shaft 8 for driving and an agitator 9 is journalled at the upper end of the post in a bearing 10. 45 The coupling between the shaft and the agitator comprises a splined nut 11 fixed to the upper end of the shaft which fits into a complementary opening in a bushing 12 moulded in a rubber hub 13. The lower end of the hub 13 is secured 50 to a flanged sleeve 14 threaded into the upper end of the agitator. The hub 13 provides a resilient support for the agitator and also provides a torsionally resilient driving connection between the oscillatory shaft 8 and the agitator. 55 This driving connection decreases the shock

resulting from the sudden reversal of the agitator, and also causes the reversal of the agitator to occur after the reversal of the shaft 8. The hub 13 also prevents leakage around the shaft 8 of water which is splashed over the upper 5 end of the hub. At the lower end of the agitator is an annulus 15 of rubber bonded to a metal ring 16 which is secured to the agitator. The annulus 15 bears on the outside of the post 7 and provides a resilient bearing for guiding 10 the agitator. This bearing prevents noise due to the wobbling of the agitator with respect to the post 7. The rubber bearing 15 has very 15 low friction with water lubrication and has the further advantage that it is not harmed by particles of grit in the washing solution.

The lower end of the post 7 is bolted to the upper side of a gear casing 15a containing the driving mechanism for oscillating the agitator shaft 8. The agitator shaft 8 extends within 20 the gear casing 15a and has a pinion 16 keyed to its lower end which is adapted to mesh with a reciprocating rack 17 to cause oscillation of the agitator. The left end of the rack is provided with a crank pin 18 which is rotatable 25 in a bearing eccentrically located in a worm wheel 19. The worm wheel is fixed to the lower end of a vertical shaft which is journalled in a bearing 21 in a tubular wringer post 22. The wringer post is clamped to the upper side of 30 the gear casing by a split clamp 23 integral with the upper wall of the gear casing. The worm wheel 19 is rotated by a worm 24 which is driven by an electric motor 25 carried on the gear casing by rubber rings 26 clamped to supports 27. An intermediate shaft 28 is connected 35 between the motor shaft 29 and the worm shaft 30 by flexible couplings 31. A thrust ball 32 is provided at the left end of the worm shaft 30. The thrust ball is adjusted by a plug 33. With 40 this arrangement the worm wheel 19 is continuously rotated in one direction by the motor and the crank pin 18 bearing in the worm wheel causes the rack 17 to be reciprocated. The body 45 of the rack is off-set and rigid so that although the end of the rack carrying the crank pin 18 is below the teeth of the worm wheel 19, the teeth of the rack and the bearing of the crank pin are in line with the teeth of the worm wheel. This reduces the load on the bearings of the 50 shaft 20 and eliminates vertical forces in the rack thrust which would have a tendency to cause slaps, resulting in objectionable noises. The reciprocating movement of the rack is guided by a guide 34a shown in Fig. 4. The guide has 55

flanges 34 which extend over the upper and lower sides of the rack. Secured to the lower flanges is a tongue 35 which slides in a groove on the underside of the rack and holds the rack in the 5 guide. From the rear edge of the guide extend ears 36 which are pivoted on the inner end of a plunger 37 slideable in the walls of the gear casing 15a. The ears 36 support the rack on the plunger and the pivotal connection between the ears 10 36 and the plunger permit pivotable movement of the guide during the reciprocating movement of the rack. Between the outside of the gear casing and the plunger 37 is arranged a coil spring 38 which biases the plunger outwardly and thereby 15 tends to move the plunger to a position in which the rack is out of engagement with the pinion. The plunger is moved inwardly by a control lever 39 pivoted on a bracket 40 secured to the outside of the gear casing. The inner end of the 20 control lever is provided with a cam surface 41 which engages a set screw 42 threaded into the plunger. When the control lever is in the position shown in full lines in Fig. 3, the plunger is pushed inwardly, thereby moving the rack 25 into mesh with the pinion. When the control lever is in the position shown in dotted lines in Fig. 3, the spring 38 moves the plunger outwardly, thereby moving the rack out of engagement with the pinion.

30 On the under side of the crank pin 18 is a pin 42a which is pressed by a coil spring 43 against the gear casing cover 44. The friction between the pin 42a and the cover of the gear casing tends to prevent over-travel of the reciprocating rack, and thereby reduces back lash between the worm and the worm gear. The friction between the pin 42a and the gear casing cover also tends to retard the rotation of the crank pin 18, and thereby tends to hold the crank 35 pin against its bearing in the worm wheel 19 during all parts of the reciprocating movement of the rack and particularly during the reversal of the reciprocating movement of the rack. The frictional force between the crank pin and its 40 bearing is always in the same direction, and causes the rack to be urged outwardly against the back of the guide 34a, thus preventing wobbling of the rack in the guide and eliminating noise from this source. When the rack is being 45 reciprocated, it is continuously held against the back of the guide 34a and the tongue 35 is then merely a means for making sure that the rack is pulled out of mesh with the pinion in case of binding between some of the parts. The pin 50 42a prevents the crank pin 18 from falling from its bearing in the worm wheel 19, and also supports the wringer shaft 20.

In order to prevent transmission of noise originating in the gearing casing to the tub and the 55 skirt 3 which serves as the tub support, I have provided a resilient mounting for the gear casing for preventing metallic contact between the gear casing and any part of the tub or the skirt. This mounting comprises rings 45 of rubber or 60 other resilient material which are arranged on either side of a flange 46 of a bracket 47 secured to the skirt 3. The parts are held in assembled relation by a bolt 48 extending through the rings 45. A clearance hole 49 in the flange 65 46 prevents metallic contact between the bolt and the flange. A resilient support of this construction is provided between the skirt 3 and each end of the gear casing. At the left end of the gear casing, the resilient support is located between the gear casing cover 44 and the

skirt. At the right end of the gear casing, the resilient support is located between a bracket 49a and the skirt. In order to prevent transmission of noise from the gear casing through the wringer post 22, I have provided a similar resilient 5 mounting between the tub and a collar 50 which is adapted to support a wringer. This mounting comprises pads 51 of resilient material which are arranged on either side of the tub and which are held in place by screws 52 threaded through 10 clearance holes in the tub into the collar. A resilient mounting is also provided between the post 7 and the bottom of the tub. This mounting comprises rings 53 of resilient material which are arranged on either side of the tub and which are 15 clamped between a flange 54 on the post 7 and a nut 55 threaded on the post. The rings 53 also serve as a water tight seal.

With this arrangement there is no metal to metal contact between the gear casing and the 20 tub or the skirt 3 and the transmission of noise is prevented by a sound insulating connection at each point of connection between the gear casing or its connected parts and the tub or the skirt. The transmission of noise originating in 25 the driving mechanism is therefore considerably decreased and quieter operation of the washing machine is obtained.

The resilient support for the driving mechanism for the washing machine has an additional function of preventing noise due to distortion of the gear casing. If the gear casing were rigidly attached to the skirt 3, any unevenness in the floor would cause distortion of the skirt and this distortion would produce a stress tending to bend 30 the walls of the gear casing. The bending of the walls of the gear casing would change the mesh of the gears journaled in the casing and would thereby produce an additional source of noise due to interference between the gear teeth. 35 With a resilient mounting for the gear casing, or any equivalent mounting such as a three point suspension of the gear casing, the distortion of the skirt, due to unevenness in the floor, or to rough handling during transit does not 40 stress the gear casing and, therefore, does not change the mesh of the gear teeth. This means that the gear mesh of the gear teeth is independent of inequalities in the floor and that 45 changes in the adjustment of the mesh of the gears are not required. Also, with this construction for supporting the gear casing, the gear casing may be made less rigid.

If the resilient mountings illustrated were replaced by rigid connections, oscillating torque applied to the agitator shaft 8 would be transmitted through the agitator post 7 and through the wringer post 22 to the tub. Since the tub is made of 50 relatively light metal these forces would cause bending of the tub, and the reaction from the tub 55 to the skirt 3 would tend to distort the walls of the gear casing. This distortion which would be an additional source of gear noise is prevented by the resilient mounting of the gear casing.

Figs. 5 and 6 show a modification of the 60 resilient connection and seal between the post 7 and the bottom of the tub. This resilient connection comprises a bushing 56 of rubber having a groove 57 into which fit the edges of the opening in the bottom of the tub. On the upper side 65 of the bushing is an inwardly extending flange 58 which is pressed outwardly when the post 7 is inserted through the bottom of the bushing. The outward movement of the flange 58 causes 70 the material of the bushing to be tightly pressed 75

against the edges of the opening in the tub and thereby provides a tight seal between the tub and the bushing. The inherent resilience of the flange 58 also effects a tight seal between the post 7 and the bushing.

What I claim as new and desire to secure by Letters Patent of the United States is:

1. In a washing machine, a tub, a shaft extending through the bottom of the tub, means for oscillating the shaft, an annulus of resilient material connected to and depending around said shaft, and an agitator supported from the lower end of said annulus.

2. In a washing machine, a tub having an opening in the bottom thereof, a tubular post projecting through said opening, a shaft extending through the post adapted to operate washing apparatus in the tub, and a seal between the post and the tub comprising a bushing of resilient material having a portion on one side of the tub and having a portion forced against the opposite side of the tub by outward deformation caused by engagement with side of said post.

3. In a washing machine, a tub having an opening in the bottom thereof, a tubular post projecting through said opening, a shaft extending through the post adapted to operate washing apparatus in the tub, and a bushing of resilient

material in said opening having a groove into which the edges of the tub fit and having an inwardly projecting portion bent outward by engagement with the sides of said post and thereby forming a water-tight seal between the bushing 5 and the tub and post.

4. In a washing machine, a tub having an opening in the bottom thereof, a tubular post projecting through said opening, a shaft extending through the post adapted to operate washing apparatus in the tub, and a resilient seal in the opening between the post and the tub for preventing transmission of vibrations from the post to the tub, said seal comprising a bushing having a groove engaging the edges of said opening and 15 an inwardly extending flange at one side of the bushing pressed outward by engagement with the sides of said post and causing the sides of the groove tightly to engage the tub.

5. In a washing machine, a tub, a shaft extending through the bottom of the tub, means for oscillating the shaft, a hub of resilient material connected to the shaft, said hub enclosing the upper end of the shaft and having an annulus of resilient material depending around the shaft, 25 and an agitator supported from the lower end of said annulus.

OSMUND HOLM-HANSEN.
